UNITED STATES PATENT OFFICE.

RICHARD B. HEWITT, OF PHILADELPHIA, PENNSYLVANIA.

DESIGN FOR STREET LANTERN AND POST.

Specification forming part of Design No. **8,010**, dated January 19, 1875; application filed December 18, 1874.
[Term of Patent 3½ years.]

To all whom it may concern:

Be it known that I, RICHARD B. HEWITT, of Philadelphia, in the county of Philadelphia and State of Pennsylvania, have invented a new Design, being for an Illuminable Street Lantern and Post; and I do hereby declare that the following is a full, clear, and exact description of the same, reference being had to the annexed drawings, making a part of this specification, and to the letters and figures of reference marked thereon.

Figure 1 of the drawings is a representation of my design, showing the lantern raised upon its post, and divided into illuminable panels, supported by the ribs of said lantern; also the panel-divisions upon the supporting-post.

My invention is a new design for a revolving street lantern and post; and consists, essentially, of an octagonal frame, the intersecting ribs of which inclose, in the form of panels, sheets of any transparent substance, and which contain one tier or more of said panels, flaring outward from the bottom, and again around the top of said frame, which top is surmounted by ornamental scroll-work, and covered by a convex cap, also surmounted by an ornamental figure, all of which is illustrated by the accompanying drawing, in which the same letters designate similar parts of my design, as hereinafter more fully described.

The letter A represents the said lantern-frame longitudinally, of octagonal form, the

lower and upper portions flaring upward and outward, as shown, its bottom and sides consisting of metallic strips or ribs, intersecting each other mostly at right angles. Said intersecting ribs a inclose, in the aforesaid panel-form, sheets b, of glass or any other transparent substance. Around the upper edge of the aforesaid flaring top of the frame A is an ornamental scroll, c, just within which is suitably fastened the lower rim of the convex cap B, which covers the said lantern, and is surmounted by an ornament, d. The whole lantern A rests upon the cap of the outer post D, which is surrounded at the top by a capital molding or beading, g, and at the base by the fillet i and the plinths j and k, as shown.

The aforesaid transparent sheets b may be temporarily covered, as may be desired, with paintings, prints, &c.; therefore

What I claim as my invention, and desire to secure by Letters Patent, is—

A design for a revolving illuminable street lantern and post, substantially as shown and described.

In testimony that I claim the above I have hereunto subscribed my name in the presence of two witnesses.

RICHARD B. HEWITT.
